DIAPHRAGM TYPE FLUID PRESSURE
SENSITIVE SWITCH

Rene Simonin, Jr., Downey, Calif., assignor to Barksdale Valves, Los Angeles, Calif., a corporation of California
Filed Apr. 6, 1965, Ser. No. 445,997
6 Claims. (Cl. 200—83)

This invention relates to a pressure switch and, more particularly, to a pressure switch having a pressure sensing diaphragm tightly sealed within a housing and responsive to fluid pressure to actuate the switch.

As is well known, pressure switches include pressure sensing means and a switch actuatable in response to the sensing means. In prior art devices, the sensing means often includes a piston slidably mounted in a cylinder and separated slightly therefrom by O-rings which are provided for sealing purposes. One difficulty with this arrangement is that the O-rings often stick to the walls of the cylinder particularly after a period of nonuse, thereby requiring an over-pressure to actuate the switch. This results in an inaccuracy in the pressure level at which the switch operates. Such pressure sensing means are also subject to leakage of the operating fluid around the O-rings. Use of a metal diaphragm, bellows, and bourdon tubes is subject to similar difficulties.

An object of this invention is to provide a pressure switch including relatively rateless pressure sensing means. Such means eliminate the need for a piston with O-rings, a metal diaphragm, bellows, or a bourdon tube. The pressure sensing means is subject to almost no movement until the desired pressure is attained, at which time the switch is immediately actuated.

Another object of this invention is to provide a pressure switch which is easily maintained and easily cleaned out if required.

A further object of this invention is to provide a pressure switch utilizing a pressure sensing means including a resilient diaphragm which is subject to very low distortion and thereby achieves an increase in the useful life thereof. Another object is to provide a non-metallic diaphragm and a pressure plate in a very shallow counterbore of a housing for limited movement therein in response to exterior fluid pressure outside of the housing. Switch means actuatable in response to such limited movement are provided within the housing.

Still another object of this invention is to provide a pressure switch including a pressure responsive diaphragm to impart movement to a pressure plate and a piston to actuate a switch and having annular retaining means for retaining the diaphragm and plate within a housing. The annular retaining means serves to hold the diaphragm and plate securely within the housing and to provide a tight seal against the ingress of fluid under pressure from the exterior of the housing. It is an object of this invention to utilize a diaphragm with an annular bead and retaining means with an annular ring to interlock with the annular bead, the annular ring being radially inward of the annular bead. Such structure improves the seal between the diaphragm and the housing. Another object is to provide an annular spacer surrounding the pressure plate and spaced slightly radially outwardly therefrom to allow free axial movement of the pressure plate. The spacer helps control movement of the pressure plate and assists in forming a fluid tight seal.

A particular object of this invention is to provide a pressure switch as described in the preceding paragraph and also including: an actuating arm pivotally mounted in the housing rotatable in one direction in response to an increase in the external fluid pressure and movement

of the piston member inwardly to actuate the switch; spring means tending to rotate the actuating arm in the opposite direction; and adjustment means for adjusting the pressure exerted by the spring means on the actuating arm to thereby vary the pressure at which the switch is actuated.

Another object of this invention is to provide a pressure switch including a pressure responsive diaphragm for imparting movement to a pressure plate and a piston to actuate a switch, annular retaining means for retaining the diaphragm and plate within a switch housing, and means for adjusting the amount of movement of the piston member. The stroke of the piston and hence of the pressure plate is preferably adjusted to approximately .010 inch.

The invention, both as to its organization and method of operation, together with further objects and advantages thereof, may best be understood by reference to the following description taken in connection with the accompanying drawing.

In the drawing:

FIG. 1 is an elevational view partially in section showing a diaphragm type fluid pressure sensitive switch;

FIG. 2 is a sectional view taken along line 2—2 in FIG. 1;

FIG. 3 is an enlarged fragmentary sectional view showing the pressure sensitive means for the pressure switch; and

FIG. 4 is an enlarged sectional view showing the resilient diaphragm used in the pressure switch.

A diaphragm type fluid pressure sensitive switch 11 includes a housing 12 comprising a hollow receptacle 13 closed by a cover 14 which is secured thereto by a plurality of screws 15. The housing 12 has a switch cavity 16 therein and a thick wall portion 17 which is substantially thicker than the remainder of the wall. The thick wall portion 17 has a cylindrical spring bore 18 and a piston bore 19 therein which is parallel to and adjacent the spring bore. The bores 18 and 19 are adjacent each other and communicate between the switch cavity 16 and the exterior of the thick wall portion 17 with the spring bore being of substantially larger diameter than the piston bore. The housing illustrated is explosion proof; however, a standard housing may be used if desired.

The outer end of the piston bore 19 is connected to a coaxial cylindrical counterbore 21 of a diameter substantially greater than the diameter of the former and having a small axial dimension, which in the embodiment illustrated is considerably smaller than the axial dimension of the piston bore. The inner end of the counterbore 21 defines an annular shoulder or over-pressure stop 22 the plane of which is substantially perpendicular to the longitudinal axis of the piston bore 19 and which is spaced slightly axially inwardly from the exterior of the thick wall portion 17. A passageway 22a which terminates in the annular shoulder 22 communicates the counterbore 21 with the exterior of the housing 12.

The housing 12 also includes a connecting port 23 into which a conduit 24 which carries a plurality of conductors 25 is threadedly secured. A switch mounting bracket 26 which may be formed integrally with the housing 12 is within the switch cavity 16. A microswitch 27 which is connected to the conductors 25 is mounted on the bracket 26 by a screw 28. The microswitch 27 includes a downwardly extending pushbutton 29, very slight inward movement of which may either open or close same. The microswitch 27 may be of any suitable design. The angular position of the microswitch 27 within the switch cavity 16 may be adjusted by the screw 28.

An actuating arm 30 is pivotally mounted at its midpoint by a pin 30a for pivotal movement within a channel

31 formed integrally with the housing 12. One end portion of the arm 30 is axially aligned with the piston bore 19 and another portion adjacent the other end thereof is axially aligned with the spring bore 18. The actuating arm 30 is an elongated solid, generally square in cross section and having an upwardly extending protrusion 32 for engaging the pushbutton 29. Rotation of the actuating arm 30 in the counterclockwise direction depresses the pushbutton 29 to actuate the microswitch 27.

Pressure responsive means are provided for imparting counterclockwise rotation to the actuating arm 30. Such means include a resilient diaphragm 33, a circular pressure plate 34, an annular spacer 35, and a cylindrical piston member 36 journaled in the piston bore 19 for axial movement therein. As most clearly seen in FIGS. 3 and 4, the resilient diaphragm 33 spans and closes the counterbore 21 and is disposed axially outwardly of the pressure plate 34. The inner face of the diaphragm 33 engages the pressure plate 34 over a major portion of its area. The diaphragm includes an annular bead 37 adjacent its periphery and extending outwardly away from the pressure plate 34. The diaphragm 33 is constructed of a resilient nonmetallic material such as neoprene.

The spacer 35 has a circular periphery and a circular opening which surrounds the pressure plate 34 spaced slightly radially outwardly therefrom to allow free axial movement of the pressure plate. The spacer 35 has a flat face which abuts tightly against the peripheral portions of the annular shoulder 22 and an opposed flat face against which the inner side of the bead 37 is tightly pressed by means which are hereinafter described. It is preferred to utilize a thin spacer constructed of stainless steel.

The pressure plate 34 is a thin circular, ridged stainless steel disc having a flat inner face 37a and an opposed flat outer face 38. The outer face 38 engages the inner face of the diaphragm 33 and the inner face 37a engages the outer end of the piston 36. The pressure plate 34 is free to move slightly axially in the counterbore 21 and is engageable with the annular shoulder 22 to define an innermost position thereof.

Annular retaining means 39 is provided for retaining the diaphragm 33, the spacer 35, and the pressure plate 34 within the counterbore 21. The retaining means 39 is secured to the housing 12 by a plurality of screws 41 and contains a stepped threaded socket 42 coaxial with the piston bore 19 and into which a conduit 43 is threaded secured. The conduit 43 supplies fluid pressure to the outer face of the diaphragm 33. The retaining means 39 includes an inwardly directed annular face 44 which firmly engages the outer face of the annular bead 37 in tight sealing relationship and causes the spacer 35 to be urged tightly against the annular shoulder 22. A ring 45 which is radially inwardly of the annular bead 37 interlocks with the latter in tight sealing engagement and an annular boss 46 extends inwardly into engagement with the outer face of the diaphragm 33. As the screws 41 are tightened, the annular face 44 engages the bead 37 causing the latter to flow radially into tight sealing engagement with the ring 45. Axial movement of the diaphragm 33 and the pressure plate 34 is limited by the boss 46 and the annular shoulder 22.

The outer end of the piston 36 engages the pressure plate 34 and the inner end thereof engages an end portion of the actuating arm 30. Inward movement of the diaphragm in response to a predetermined increase in fluid pressure in the conduit 43 will move the pressure plate 34 and the piston member 36 inwardly to rotate the actuating arm 30 counterclockwise to actuate the microswitch 27.

Means is provided for adjusting the amount of axial movement of the piston 36 in response to such increase in external fluid pressure. Such means includes an adjusting nut 47 threadedly secured on the inner end portion of the piston 36. The outer face of the nut 47 engages

the wall of the switch cavity 16 adjacent the piston bore 19 and is of a type which will maintain a fixed angular orientation relative to the piston 36 after being initially set. It is apparent that by turning the nut 47, the inner end of the piston 36 and, hence, the protrusion 32 can be moved toward or away from the pushbutton 29. The nut 47 is preferably factory adjusted so that approximately .010 inch of movement of the pressure plate 34 and, hence, of the piston 36 and protrusion 32 is required to actuate the microswitch 27.

To resist the force of the external fluid pressure acting on the outer face of the diaphragm 33, a spring 48 is provided in the spring bore 18 which tends to rotate the actuating arm 30 in the clockwise direction. An adjustment screw 49 is screwed into the spring bore 18 adjacent and closing the outer end thereof, the screw being axially movable in the spring bore. The annular retaining means 39 has a passageway 51 extending therethrough to permit controlling of the position of the adjusting screw 49 in the bore 18. A set screw 52 urges a soft slug 53 of metal such as copper into engagement with the side wall of the adjusting screw 49 to prevent movement thereof from the set position. The spring 48 engages the adjusting screw 49 at one end and a retainer 54 at the other end and urges the latter into engagement with the other end portion of the actuating arm 30. Thus, by adjusting the screw 49 the force of the spring and, hence, the value of fluid pressure required to actuate the microswitch 27 are adjusted.

In operation of the pressure switch, the nut 47 is adjusted to control the stroke of the piston 36. Turning of the adjusting screw 49 sets the value of fluid pressure required to operate the microswitch 27. When this setting has been made, the set screw 52 is tightened to assure that such setting will be maintained. An increase in the fluid pressure in the conduit 43 will cause the diaphragm 33, the pressure plate 34, and the piston 36 to move inwardly to rotate the actuating arm 30 counterclockwise to actuate the microswitch 27. The microswitch 27 is preferably actuated before the plate 34 engages the annular shoulder 22. Thus, the latter defines an over-pressure stop which limits the innermost position of the plate 34 when the diaphragm 33 is subjected to a greater pressure than is necessary to actuate the switch 27. Such actuation of the microswitch may result in opening or closing of one or several external circuits or the opening of one circuit and the closing of another depending upon the particular type of switch selected. Upon a decrease in fluid pressure, the force of the spring 48 will cause the actuating arm 30 to rotate clockwise to release the force on the pushbutton 29 and force the piston 36, plate 34, and diaphragm 33 outwardly. The passageway 22a allows axial movement of the plate 34 and diaphragm 33 within the counterbore 21 without a dashpot effect by permitting intake and exhausting of air from the counterbore. Such release of the pushbutton 29 may have various results on the external circuitry depending upon the type of microswitch selected.

An important feature of this invention is that the diaphragm 33 and the pressure plate 34 experience only very slight axial movement prior to actuation of the microswitch 27. Thus, diaphragm distortion is reduced and the life thereof is increased. No over-pressure is required to move the diaphragm 33 and the pressure at which the microswitch 27 is actuated may be very accurately controlled. The seal between the diaphragm 33 and the retaining means 39 is very tight and substantially prevents any of the fluid under pressure in the socket 42 from passing into the switch cavity 16. The adjusting nut 47 allows accurate control of the stroke of the piston 36, such stroke preferably being in the neighborhood of .010 inch.

Many changes, modifications, and substitutions can be made by one having ordinary skill in the art without departing from the spirit and scope of this invention, and,

accordingly, I do not desire to be limited by the specific embodiment described herein, but desire to be afforded the full scope of the following claims.

What is claimed is:

1. In a pressure switch, the combination of:

a housing having an outside wall and a switch cavity therein, one portion of said wall being substantially thicker than the remainder of said wall, said portion having first and second cylindrical bores therein parallel to and adjacent to each other and communicating between said cavity and the exterior of said wall, said first bore being of substantially larger diameter than said second bore, the outer end of said second bore being provided with a connected cylindrical counterbore of a diameter substantially greater than the diameter of said first bore; 15

an actuating arm pivotally mounted in said cavity with one end portion thereof in alignment with said first bore and another portion thereof adjacent the other end of said arm in alignment with said second bore; 20 electrical switch means in said cavity actuated by pivotal movement of said actuating arm upon the occurrence of such pivotal movement;

a circular pressure plate in said counterbore adjacent to said second bore and axially movable in said counterbore; 25

a resilient diaphragm in said counterbore and spanning and closing same, said diaphragm being disposed outwardly of said pressure plate and engaging the same over a major portion of its area, the outer face of said diaphragm being exposed to external fluid pressure outside said wall; 30

annular retaining means in said counterbore for retaining said diaphragm and said pressure plate therein;

a cylindrical piston member journalled in said second bore for axial movement therein, the outer end of said piston member engaging said pressure plate and the inner end thereof engaging said actuating arm, whereby inward movement of said diaphragm in response to an increase in said external fluid pressure will move said pressure plate and said piston member inwardly, to rotate said actuating arm in one direction to actuate said switch means; 40

adjustment means in said first bore adjacent the outer end thereof and closing the same, said adjustment means being axially movable in said first bore and being accessible from the exterior of said first bore; and

spring means in said first bore between said adjustment means and said one end portion of said actuating arm, exerting pressure on said actuating arm tending to rotate said actuating arm in a direction opposite to said one direction, such movement of said adjustment means varying the pressure exerted by said spring means on said actuating arm. 50

2. In a pressure switch, the combination of:

a housing having an outside wall and a switch cavity therein, one portion of said wall being substantially thicker than the remainder of said wall, said portion having first and second cylindrical bores therein parallel to and adjacent to each other and communicating between said cavity and the exterior of said wall, said first bore being of substantially larger diameter than said second bore, the outer end of said second bore being provided with a connected cylindrical counterbore of a diameter substantially greater than the diameter of said first bore; 60

an actuating arm pivotally mounted in said cavity with one end portion thereof in alignment with said first bore and another portion thereof adjacent the other end of said arm in alignment with said second bore; electrical switch means in said cavity actuated by pivotal movement of said actuating arm upon the occurrence of such pivotal movement; 70

a circular pressure plate in said counterbore adjacent to said second bore and axially movable in said counterbore;

a resilient diaphragm in said counterbore and spanning and closing same, said diaphragm being disposed outwardly of said pressure plate and engaging the same over a major portion of its area, the outer face of said diaphragm being exposed to external fluid pressure outside said wall, said diaphragm having an annular bead adjacent its periphery and extending outwardly away from said pressure plate; an annular spacer surrounding said pressure plate and spaced slightly radially outwardly therefrom to allow free axial movement of said pressure plate, said spacer engaging said annular bead on the inner side thereof;

retaining means secured to said housing for clamping said annular bead into engagement with said spacer; a cylindrical piston member journalled in said second bore for axial movement therein, the outer end of said piston member engaging said pressure plate and the inner end thereof engaging said actuating arm, whereby inward movement of said diaphragm in response to an increase in said external fluid pressure will move said pressure plate and said piston member inwardly, to rotate said actuating arm in one direction to actuate said switch means;

adjustment means in said first bore adjacent the outer end thereof and closing the same, said adjustment means being axially movable in said first bore and being accessible from the exterior of said first bore; and

spring means in said first bore between said adjustment means and said one end portion of said actuating arm, exerting pressure on said actuating arm tending to rotate said actuating arm in a direction opposite to said one direction, such movement of said adjustment means varying the pressure exerted by said spring means on said actuating arm.

3. In a pressure switch, the combination of:

a housing having an outside wall and a switch cavity therein, one portion of said wall being substantially thicker than the remainder of said wall, said portion having first and second cylindrical bores therein parallel to and adjacent to each other and communicating between said cavity and the exterior of said wall, said first bore being of substantially larger diameter than said second bore, the outer end of said second bore being provided with a connected cylindrical counterbore of a diameter substantially greater than the diameter of said first bore, the inner end of said counterbore defining an annular shoulder; an actuating arm pivotally mounted in said cavity with one end portion thereof in alignment with said first bore and another portion thereof adjacent the other end of said arm in alignment with said second bore; electrical switch means in said cavity actuated by pivotal movement of said actuating arm upon the occurrence of such pivotal movement;

a circular pressure plate in said counterbore adjacent to said second bore and axially movable in said counterbore;

a resilient diaphragm in said counterbore and spanning and closing same, said diaphragm being disposed outwardly of said pressure plate and engaging the same over a major portion of its area, the outer face of said diaphragm being exposed to external fluid pressure outside said wall, said diaphragm having an annular bead adjacent its periphery and extending outwardly away from said pressure plate;

an annular spacer surrounding said pressure plate and spaced slightly radially outwardly therefrom to allow free axial movement of said pressure plate, said spacer abutting said annular shoulder and engaging said annular bead on the inner side thereof;

retaining means secured to said housing for clamping said annular bead into engagement with said spacer and for holding said spacer firmly against said shoulder, said retaining means including an annular ring interlocking with said annular bead, said annular ring being radially inwardly of said annular bead; a cylindrical piston member journaled in said second bore for axial movement therein, the outer end of said piston member engaging said pressure plate and the inner end thereof engaging said actuating arm, whereby inward movement of said diaphragm in response to an increase in said external fluid pressure will move said pressure plate and said piston member inwardly, to rotate said actuating arm in one direction to actuate said switch means; adjustment means in said first bore adjacent the outer end thereof and closing the same, said adjustment means being axially movable in said first bore and being accessible from the exterior of said first bore; and

spring means in said first bore between said adjustment means and said one end portion of said actuating arm, exerting pressure on said actuating arm tending to rotate said actuating arm in a direction opposite to said one direction, such movement of said adjustment means varying the pressure exerted by said spring means on said actuating arm.

4. In a pressure switch, the combination of:

a housing having an outside wall and a switch cavity therein, one portion of said wall being substantially thicker than the remainder of said wall, said portion having first and second cylindrical bores therein parallel to and adjacent to each other and communicating between said cavity and the exterior of said wall, said first bore being of substantially larger diameter than said second bore, the outer end of said second bore being provided with a connected cylindrical counterbore of a diameter substantially greater than the diameter of said first bore and having a small axial dimension, the inner end of said counterbore defining an annular shoulder which is spaced slightly axially inwardly from the exterior of said wall;

an actuating arm pivotally mounted in said cavity with one end portion thereof in alignment with said first bore and another portion thereof adjacent the other end of said arm in alignment with said second bore; electrical switch means in said cavity actuated by slight pivotal movement of said actuating arm upon the occurrence of such pivotal movement;

a circular pressure plate in said counterbore adjacent to said second bore and slightly axially movable in said counterbore, said pressure plate being engageable with said annular shoulder to define the innermost position of said pressure plate;

a resilient diaphragm in said counterbore and spanning and closing same, said diaphragm being disposed outwardly of said pressure plate and engaging the same over a major portion of its area, the outer face of said diaphragm being exposed to external fluid pressure outside said wall, said diaphragm being movable slightly inwardly in response to said fluid pressure until said pressure plate engages said annular shoulder;

retaining means in said counterbore for retaining said diaphragm and said pressure plate therein;

a cylindrical piston member separate from said pressure plate journaled in said second bore for axial movement therein, the outer end of said piston member engaging said pressure plate and the inner end thereof engaging said actuating arm, whereby slight inward movement of said diaphragm in response to an increase in said external fluid pressure will move said pressure plate and said piston member slightly

inwardly, to rotate said actuating arm in one direction to actuate said switch means;

adjustment means in said first bore adjacent the outer end thereof and closing the same, said adjustment means being axially movable in said first bore and being accessible from the exterior of said first bore; and

spring means in said first bore between said adjustment means and said one end portion of said actuating arm, exerting pressure on said actuating arm tending to rotate said actuating arm in a direction opposite to said one direction, such movement of said adjustment means varying the pressure exerted by said spring means on said actuating arm.

5. In a pressure switch, the combination of:

a housing having an outside wall and a switch cavity therein, one portion of said wall being substantially thicker than the remainder of said wall, said portion having first and second cylindrical bores therein parallel to and adjacent to each other and communicating between said cavity and the exterior of said wall, said first bore being of substantially larger diameter than said second bore, the outer end of said second bore being provided with a connected cylindrical counterbore of a diameter substantially greater than the diameter of said first bore;

an actuating arm pivotally mounted in said cavity with one end portion thereof in alignment with said first bore and another portion thereof adjacent the other end of said arm in alignment with said second bore; electrical switch means in said cavity actuated by pivotal movement of said actuating arm upon the occurrence of such pivotal movement;

a circular pressure plate in said counterbore adjacent to said second bore and axially movable in said counterbore;

a resilient diaphragm in said counterbore and spanning and closing same, said diaphragm being disposed outwardly of said pressure plate and engaging the same over a major portion of its area, the outer face of said diaphragm being exposed to external fluid pressure outside said wall;

annular retaining means in said counterbore for retaining said diaphragm and said pressure plate therein;

a cylindrical piston member journaled in said second bore for axial movement therein, the outer end of said piston member engaging said pressure plate and the inner end thereof engaging said actuating arm, whereby inward movement of said diaphragm in response to an increase in said external fluid pressure will move said pressure plate and said piston member inwardly, to rotate said actuating arm in one direction to actuate said switch means;

means for adjusting the amount of axial movement of said piston member in response to said increase in said external fluid pressure;

adjustment means in said first bore adjacent the outer end thereof and closing the same, said adjustment means being axially movable in said first bore and being accessible from the exterior of said first bore; and

spring means in said first bore between said adjustment means and said one end portion of said actuating arm, exerting pressure on said actuating arm, tending to rotate said actuating arm in a direction opposite to said one direction, such movement of said adjustment means varying the pressure exerted by said spring means on said actuating arm.

6. In a pressure switch, the combination of:

a housing having an outside wall and a switch cavity therein, one portion of said wall being substantially thicker than the remainder of said wall, said portion having first and second cylindrical bores therein parallel to and adjacent to each other and communicating between said cavity and the exterior of said

75

wall, said first bore being of substantially larger diameter than said second bore, the outer end of said second bore being provided with a connected cylindrical counterbore of a diameter substantially greater than the diameter of said first bore; 5
an actuating arm pivotally mounted in said cavity with one end portion thereof in alignment with said first bore and another portion thereof adjacent the other end of said arm in alignment with said second bore; 10
electrical switch means in said cavity actuated by pivotal movement of said actuating arm upon the occurrence of such pivotal movement; 15
a circular pressure plate in said counterbore adjacent to said second bore and axially movable in said counterbore; 20
a resilient diaphragm in said counterbore and spanning and closing same, said diaphragm being disposed outwardly of said pressure plate and engaging the same over a major portion of its area, the outer face of said diaphragm being exposed to external fluid pressure outside said wall; 25
annular retaining means in said counterbore for retaining said diaphragm and said pressure plate therein; 30
a cylindrical piston member journaled in said second bore for axial movement therein, the outer end of said piston member engaging said pressure plate and the inner end thereof engaging said actuating arm, whereby inward movement of said diaphragm in response to an increase in said external fluid pressure will move said pressure plate and said piston member

inwardly, to rotate said actuating arm in one direction to actuate said switch means; 5
a threaded adjusting nut on the inner end portion of said piston for adjusting the amount of axial movement of said piston in response to said increase in said external fluid pressure, said adjusting nut being adjustable to limit said axial movement of said piston to approximately .010 inch; 10
adjustment means in said first bore adjacent the outer end thereof and closing the same, said adjustment means being axially movable in said first bore and being accessible from the exterior of said first bore; 15
and
spring means in said first bore between said adjustment means and said one end portion of said actuating arm, exerting pressure on said actuating arm tending to rotate said actuating arm in a direction opposite to said one direction, such movement of said adjustment means varying the pressure exerted by said spring means on said actuating arm.
